UNITED STATES PATENT OFFICE.

WILLIAM H. PERRY, OF CONCORD, NEW HAMPSHIRE.

DESIGN FOR A MONUMENT.

SPECIFICATION forming part of Design No. 26,908, dated April 13, 1897.

Application filed February 25, 1897. Serial No. 625,055. Term of patent 14 years.

To all whom it may concern:

Be it known that I, WILLIAM H. PERRY, a citizen of the United States, residing at Concord, in the county of Merrimac and State of New Hampshire, have invented and produced a new and original Design for Monuments; and I do hereby declare the following to be a full, clear, and exact description of the invention, such as will enable others skilled in the art to which it appertains to make and use the same.

The leading features of my design consist in the particular shape and configuration of the shaft, and especially its ornamental top, with the character of the surfaces of the different parts, all of which will be fully set forth in the following specification and claim and clearly illustrated in the drawing accompanying and forming a part of the same, reference being had to the drawing both by figures and letters.

The base 1 is oblong, having four vertical sides terminating in an obtuse frustum of a pyramid, (represented at 2.) The pedestal 3 rests upon the frustum 2 and has four vertical sides which terminate in an acute frustum of a pyramid, as at 4, on one or more sides of which will be formed a raised tablet 5. The frustum 4 supports the shaft 6, which

is also oblong in form, its sides being ornamented each by a tablet having a surface of a different character, as at 7.

The shaft is provided with an overhanging top piece or cap 8, of pyramid form, each of the four corners of which are ornamented by a raised tablet 9, of semicircular form in cross-section and tapering toward the apex of the top 8, said tablets represented as being formed of overlapping parts 10. One or both of the long sides of said cap 8 are provided with a raised tapering tablet 11, upon the top of which appears the shell ornament 12, which is made to form the end of a tapering fluted tablet 13, as shown.

The surfaces are finished variously, as indicated best by the reference-letters, A representing rockwork, B hammered work, and C polished work.

Having described my new design, what I claim is—

The design for a monument substantially as herein shown and described.

In testimony whereof I affix my signature in presence of two witnesses.

WILLIAM H. PERRY.
